GRADING MACHINE

Filed Jan. 2, 1932

Fig. 1.

UNITED STATES PATENT OFFICE

BENJAMIN H. FLYNN, OF ALEXANDRIA, LOUISIANA

GRADING MACHINE

Application filed January 2, 1932. Serial No. 584,494.

The invention relates to a grading machine designed primarily for preparing a sub-grade on which to lay a concrete or other highway, and it relates more specifically to a 5 grading machine having a rotary grader provided with cutters which are adjustable to transversely shape the grade as required, giving said grade a transversely convex form, a transversely concave form, or a transversely straight form, as desired. In adjusting the cutters, difficulty has heretofore been experienced and it has been almost impossible to obtain an accurate adjustment. It is one 10 object of my invention however to provide the machine with a templet which enables strictly accurate cutter adjustments to be made.

A further aim is to provide for changing the shape of the templet according to the shape desired for the grade.

20 Yet another object is to provide for shifting the templet into operative relation with the rotary grader when cutter adjustments are to be made, and for shifting said templet to an out-of-the-way position when its use is not required.

A still further aim is the provision of a construction which is rather simple and inexpensive, is easily operated, and long-lived.

With the foregoing in view, the invention 30 resides in the novel subject matter hereinafter described and claimed, description being accomplished by reference to the accompanying drawing.

Fig. 1 is a longitudinal sectional view 35 through a sub-grading machine improved in accordance with the present invention.

Fig. 2 is a fragmentary plan view as indicated by the arrow A of Fig. 1, showing the templet in operative relation with the 40 rotary cutter-carrying grader.

A grading machine is shown denoted in a general way by the numeral 5, said grading machine having wheels 6 which travel upon side forms 7 between which the grade 8 is prepared. The machine 5 embodies a rotary grader 9 elongated in a direction transverse to the line of travel of the machine, said rotary grader 9 embodying cutters 10 adjustably held by appropriate clamping means 11 45 so that they may be adjusted toward and

from the axis of the grader 9, thereby so changing the shape of the latter as to impart the desired cross-sectional shape to the grade 8. The earth excavated by the rotary grader 9, is rearwardly thrown over a guide plate 12 55 onto a table 13 and is removed from the latter by a conveyor 14.

The gist of the present invention relates to a novel means to facilitate adjustment of the cutters 10 rather than to any features of the machine so far briefly described. The templet is in the form of a suitable bar 15 which is uni-directional with the rotary grader 9 and is substantially parallel with the axis of the latter. This bar 15 is resilient and provision is made for springing it into different shapes, according to the shape which must be imparted to the grade 8, by the cutters 10. In the present showing, adjusters 16 which are disposed transverse to the bar 15, are connected at one end with the latter, said adjusters being spaced apart along the length of said bar. The other ends of the adjusters 16 are connected with the frame of the machine 5, and the connections are such that the adjusters 16 60 and the bar 15 may be moved into and out of operative relation with the rotary grader 9, as shown by the full and dotted lines of Fig. 1. The adjusters 16 are longitudinally extensible and retractile and hence by adjusting 65 them, the shape of the bar 15 may be changed as required, and when all of the cutters 10 are adjusted so that they will come into contact with the bar 15 or substantially in contact therewith, it is known that the necessary accurate 70 adjustments of said cutters, have been attained.

Each adjuster 16 preferably consists of two rods 17 and 18 connected by a turn-buckle 19, the rod 17 being suitably connected at 20 75 with the bar 15, while the rod 18 is pivotally connected at 21 with the frame of the machine 5. This frame, in the construction shown, embodies a transverse bar 22 on which all of the adjusters 16 are pivotally mounted by 80 the means 21.

Normally, the bar 15 and the adjusters 16 85 occupy the positions shown in dotted lines in Fig. 1 and hence, they are entirely out of the path of the rotary grader 9. When the cut- 90

ters 10 of this grader are to be adjusted however, the adjusters 16 and bar 15 are swung to the position shown in full lines in Figs. 1 and 2, and by means of said adjusters, the shape of the bar 15 is changed according to 5 the shape to be imparted to the grade 8. The parts may be held in the full line position of Figs. 1 and 2, either by friction in the connections 21, or by other appropriate means, 10 and it will be seen that when all of the cutters 10 are so adjusted that they will just clear the bar 15, the grader 9 will have been properly conditioned for accurately cutting the grade.

Excellent results are obtainable from the 15 details disclosed and they may therefore be followed if desired. However, within the scope of the invention as claimed, numerous variations may be made.

I claim:—

1. In a grading machine having a rotatable grader provided with adjustable cutters for changing its shape according to the transverse shape desired for the grade; a templet carried by the machine to assist in accurately adjusting said cutters.

2. In a grading machine having a rotatable grader provided with adjustable cutters for changing its shape according to the transverse shape desired for the grade; a templet to 30 assist in accurately adjusting said cutters, and means mounting said templet on the machine for movement into and from operative relation with said rotatable grader.

3. In a grading machine having a rotatable grader provided with adjustable cutters for changing its shape according to the transverse shape desired for the grade; a templet to assist in accurately adjusting said cutters, and means pivotally mounting said templet 40 on the machine and allowing swinging of said templet into and from operative relation with said rotatable grader.

4. In a grading machine having a rotatable grader provided with adjustable cutters for changing its shape according to the transverse shape desired for the grade; a templet to assist in accurately adjusting said cutters, and adjusting means for changing the shape of said templet according to the shape desired 50 for the grade.

5. In a grading machine having a rotatable grader provided with adjustable cutters for changing its shape according to the transverse shape desired for the grade; a templet carried by the machine to assist in accurately adjusting said cutters, and adjusting means for changing the shape of said templet according to the shape desired for the grade.

6. In a grading machine having a rotatable grader provided with adjustable cutters for changing its shape according to the transverse shape desired for the grade; a templet to assist in accurately adjusting said cutters, 65 adjusting means connected with said templet

for changing the shape of the latter according to the shape desired for the grade, and means mounting said adjusting means on the machine.

7. In a grading machine having a rotatable 70 grader provided with adjustable cutters for changing its shape according to the transverse shape desired for the grade; a templet to assist in accurately adjusting said cutters, adjusting means connected with said templet 75 for changing the shape of the latter according to the shape desired for the grade, and means movably mounting said adjusting means on the machine and allowing such movement of said adjusting means and 80 templet as to position the latter either in or out of operative relation with said rotatable grader.

8. In a grading machine having a rotatable 85 grader elongated in a direction transverse to the path of travel of the machine, said rotatable grader being provided with adjustable cutters for changing its shape according to the shape desired for the grade, a resilient templet bar carried by the machine, 90 said templet bar being substantially co-extensive in length with said rotatable grader and substantially parallel with the axis thereof and serving as a guide when adjusting said cutters, and means for springing said bar into different shapes according to the shape 95 desired for the grade.

9. In a grading machine having a rotatable 100 grader elongated in a direction transverse to the path of travel of the machine, said rotatable grader being provided with adjustable cutters for changing its shape according to the shape desired for the grade, a resilient templet bar substantially co-extensive 105 in length with said rotatable grader and substantially parallel with the axis thereof, said templet bar serving as a guide when adjusting said cutters, and longitudinally extensible and retractile adjusters transverse to said templet bar and connected at one end with longitudinally spaced portions of the latter, the other ends of said adjusters being connected with the frame of the machine, whereby said adjusters may be used to vary the shape of the templet bar according 110 to the shape desired for the grade.

10. In a grading machine having a rotatable grader elongated in a direction transverse to the path of travel of the machine, said rotatable grader being provided with 115 adjustable cutters for changing its shape according to the shape desired for the grade, a resilient templet bar substantially co-extensive in length with said rotatable grader and substantially parallel with the axis thereof, said templet bar serving as a guide when adjusting said cutters, longitudinally extensible and retractile adjusters transverse to said templet bar and connected at one end with longitudinally spaced portions of the 120

125

latter, and means movably mounting the other ends of said adjusters on the frame of the machine, said means allowing such movement of said adjusters and templet bar as to position the latter either in or out of operative relation with said rotatable grader, said adjusters being operable to vary the shape of the templet bar according to the shape desired for the grade.

- 10 11. An adjustable templet comprising an elongated bar, adjusting devices extending laterally from and spaced apart along the length of said bar, each of said adjusting devices embodying two end sections and a turn-buckle connecting said end sections, the end sections at one end of said adjusting devices being connected to one side of said bar, and a rigid support to which the end sections at the other ends of said adjusting devices are connected.
- 15 12. An adjustable templet comprising an elongated bar, adjusting devices extending laterally from and spaced apart along the length of said bar, each of said adjusting devices being connected at one end with one side of said bar, and brackets to which the other ends of said adjusting devices are pivoted on axes extending longitudinally of said bar, said brackets having portions for attachment to a support.
- 20 25 30 In testimony whereof I affix my signature.
